DFS. 2045

C. J. Scovell of Philadelphia Pennsylvania

Letter Patent No. 2.045 Dated April 11. 1865.

Design for a Clock Front

The schedule referred to in this Letter Patent and making part of the same

To all whom it may concern:

Be it known that I C. J. Scovell of Philadelphia county of Philadelphia state of Pennsylvania have invented or produced a new and original design for a Clock Front, and I do hereby declare the accompanying drawing with the following explanation of the same to form a full, clear and exact description of the said Design.

My Design relates to the shape and configuration of the front frame or door of a clock case, this frame consisting of the base piece A the two uprights B and B', and cross pieces D and E, joined together and arranged in respect to each other as illustrated in the accompanying drawing.

The upper space F, in the frame is of such dimensions that the dial of the clock can be seen through it.

Each end of each of the pieces, composing the clock front projects beyond that piece to which it is secured as illustrated in the drawing so that the whole may present a rustic appearance.

I claim

The shape and configuration of the clock front substantially as represented in and by the accompanying drawing.

In testimony whereof I have signed my name to this specification in the presence of two subscribing witnesses
